(57) **CLAIM**

The ornamental design for a key tag, as shown and described.

DESCRIPTION

FIG. 1 is a front perspective view of my design;
FIG. 2 is a rear perspective view;

FIG. 3 is a front elevational view;

FIG. 4 is a rear elevational view;

FIG. 5 is a top plan view;

FIG. 6 is a bottom plan view;

FIG. 7 is a right side view;

FIG. 8 is a left side view;

FIG. 9 is a front perspective view of a second embodiment of my design;

FIG. 10 is a rear perspective view of a second embodiment of my design;

FIG. 11 is a front perspective view of a third embodiment of my design;

FIG. 12 is a rear perspective view of a third embodiment of my design;

FIG. 13 is a front perspective view of a fourth embodiment of my design;

FIG. 14 is a rear perspective view of a fourth embodiment of my design;

FIG. 15 is a front perspective view of a fifth embodiment of my design;

FIG. 16 is a rear perspective view of a fifth embodiment of my design;

FIG. 17 is a top plan view of FIG. 16;

FIG. 18 is a bottom plan view of FIG. 16;

FIG. 19 is a right side view of FIG. 16;

FIG. 20 is a left side view of FIG. 16;

FIG. 21 is a front perspective view of a sixth embodiment of my design; and,

FIG. 22 is a rear perspective view of a sixth embodiment of my design.

The broken lines showing the key ring and loop in the figures are for illustrative purposes only and forms no part of the claimed design.
